UNITED STATES PATENT OFFICE.

GEORGE HENRY WHEARY, OF RACINE, WISCONSIN.

DESIGN FOR A TRUNK LOCK.

60,278.

Specification for Design.

Patented Jan. 17, 1922.

Application filed March 21, 1921. Serial No. 454,290. Term of patent 14 years.

To all whom it may concern:

Be it known that I, GEORGE HENRY WHEARY, a citizen of the United States, residing at Racine, in the county of Racine and State of Wisconsin, have invented a new, original, and ornamental Design for a Trunk Lock, of which the following is a description, reference being had to the accompanying drawing, forming part thereof.

Fig. 1 is a front view of the lock showing my new design; and

Fig. 2 is an edge view thereof.

I claim:

The ornamental design for a trunk lock, as shown.

GEORGE HENRY WHEARY.
